UNITED STATES PATENT OFFICE.

LEVI I. DARBY, OF NEWARK, NEW JERSEY.

COLLAPSIBLE RACK.

1,297,548.

Specification of Letters Patent. Patented Mar. 18, 1919.

Application filed March 6, 1918. Serial No. 220,683.

To all whom it may concern:

Be it known that I, LEVI I. DARBY, a citizen of the United States, residing at Newark, in the county of Essex and State of New Jersey, have invented certain new and useful Improvements in Collapsible Rack; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

15 The present invention relates, generally, to a collapsible rack for cans, preserving jars, bottles, etc.; and the invention has reference, more particularly, to a novel utensil which is adapted as an aid in handling jars, 20 and the like, by the housewife during the processes of preserving fruit, vegetables, and other products, the same being of such a novel construction as to be readily folded up, when not in use, so as to occupy little 25 storage space.

The invention has for its principal object to provide a novel collapsible rack having a novel means for articulating its various parts, and a novel means for locking the same in its opened operative position; the same providing, furthermore, a very clean, sanitary, durable and easily manipulated utensil for the purposes mentioned.

With the various objects of my present invention in view, the same consists, primarily, in the novel construction of collapsible rack hereinafter set forth; and the invention consists, furthermore, in the novel arrangements and combinations of the various devices and parts, as well as in the details of the construction thereof, all of which will be hereinafter more fully described in the following specification and then finally embodied in the appended claims.

45 The invention is clearly illustrated in the accompanying drawings, in which:—

Figure 1 is a side view of the novel collapsible rack in its open position ready for use; Fig. 2 is a top plan view of the same 50 in open position; Fig. 3 is a side view of the same in collapsed position; Fig. 4 is a transverse section taken on line 4—4 in said Fig. 1, looking toward the left; and Fig. 5 is a transverse section taken on line 5—5 in said 55 Fig. 1, looking toward the right.

Fig. 6 is an enlarged detail side view of

the means for locking the rack in open position; Fig. 7 is a similar detail view of a bearing portion of the device, Fig. 8 is a front edge view of the same; and Fig. 9 is a similar front edge view illustrating the way of opening said bearing for assembling purposes.

Similar characters of reference are employed in all of the hereinafter described views, to indicate corresponding parts.

Referring now to the said drawings, the reference character 1 indicates the complete collapsible rack made according to and embodying the principles of my present invention, the same comprising a bottom member consisting of a rectangular frame having longitudinal side portions 2 and transverse end portions 3 integrally formed, a suitable uniting sleeve 4, or other suitable means, joining together the abutting ends of the frame, preferably at a side portion 2. Arranged intermediate of said side portions 2 are a plurality of supporting bars 5. Said supporting bars 5 are longitudinally disposed, and are provided at their ends with eye-portions or loops 6 which embrace said end portions 3 to secure said bars 5 in place. The frame thus formed is tinned after its parts are assembled together, and the tinning serves to solder the eye-portions or loops 6 to the end-portions 3 to fix said bars 5 and the sleeve 4 in place.

The reference character 7 indicates normally vertical corner pieces or risers respectively pivotally connected at the corners of said bottom member. Said corner pieces or risers are preferably made of flat metal. Fixed to and extending between the lower ends of laterally opposite corner pieces or 95 risers, are transversely extending spreader or spacer rods 8, which serve to secure said laterally opposite corner pieces or risers together, and maintained in proper laterally spaced relation one to the other. The ends 100 of said rods are fixed in perforations provided in said corner pieces or risers. Connected integrally with the outwardly facing marginal edge of each corner piece or riser, adjacent to the upper end of the same, are a pair of vertically spaced outwardly extending lugs which are curled inwardly to form receiving socket portions 9. Fixed in said socket portions 9 of laterally opposite corner pieces or risers 7 are the ends 10 of 110 an upwardly projecting handle loop 11, which thus extend vertically upward from

the upper ends of laterally opposite corner pieces or risers 7. Said handle loop ends 10 and said spreader rods 8 are fixed in place by a wash of tin when the parts thus 5 assembled are dipped in a tin bath for tinning the surfaces thereof.

Pivottally connected with said corner pieces or risers 7, adjacent to their upper ends, is a rectangular top frame having longitudinal side portions 12 and transverse end portions 13 integrally formed, a suitable uniting sleeve 14, or other suitable means, joining together the abutting ends of the frame, preferably at a side portion 12. Arranged intermediate of said end portions 13, in equally spaced positions, are a plurality of transverse bars 15, the ends of which are turned around said longitudinal side portions 12 to provide embracing eye portions 20 or loops 16 to secure said bars 15 in place. The top frame thus formed is tinned after its parts are assembled together, and the tinning serves to solder the eye portions or loops 16 to the side portions 12 to fix said 25 bars 15 and the sleeve 14 in place.

The said corner-pieces or risers are each provided in their inwardly facing marginal edges, adjacent to their lower ends with a novel construction of bearing portion where- 30 by the bottom frame member is pivotally connected therewith. These novel bearing portions comprise a semi-circular seat 17, cut or notched in the material of each corner piece or riser. Each corner piece or riser 35 is cut away at the inner side of its seat in the form of a vertical slot 18 thus providing a tongue 19, integrally formed with each corner piece or riser, and extending downwardly and vertically toward said seat 17, 40 the free end of each tongue also having cut or notched therein a semi-circular seat 20 adapted to be alined above said seat 17, and when so alined to form in conjunction therewith a circular bearing opening. When it 45 is desired to assemble in proper pivoted relation to said corner-pieces or risers 7 said bottom frame member, said tongues 19 are bent outwardly away from the seats 17 (as shown in Fig. 9 of the drawings) thus providing 50 openings or gaps through which the transverse end portions 3 of said bottom frame member may be inserted to seat the same in said semi-circular seats 17 of said corner-pieces or risers 7. After the end 55 portions 3 are thus related to the seats 17, the tongues 19 are then bent back into normal position to carry their seats 20 in straddled relation over said end portions 3 and alined with the seats 17, to combine there- 60 with in forming a circular bearing in which said end portions 3 of the bottom frame member are pivotally journaled, as will be clearly apparent from an inspection of Fig. 6 of the drawings. In like manner said 65 corner pieces or risers are provided in their

inwardly facing marginal edges, adjacent to their upper ends, with a similar bearing construction, comprising the semi-circular seat 17', the vertical slot 18', and the tongue 19' having the reverse seat 20' for alinement 70 with the seat 17', said bearing portions providing a pivotal connection of the end portions 13 of said top frame member with the corner pieces or risers 7, the manner of assembling said parts being the same as above 75 described.

It will thus be apparent that the bottom frame member and top frame member are pivotally connected with the corner-pieces or risers, the latter being arranged in laterally opposite interconnected pairs providing end frame members, and that consequently by turning downwardly the end frame-members thus provided, the rack or carrier may be collapsed into a substantially flat bulk as 85 shown in Fig. 3 of the drawings.

In order to properly limit the unfolding or setting up movement of the end frame members, so that the same cannot swing beyond a normal vertical plane, I provide the 90 corner-pieces or risers forming one end frame member with stop means for limiting the upward swinging movement of the end frame members. This stop means comprises an inwardly extending lug 21, connected 95 with each of the laterally opposite corner pieces or risers which form one end member, the same extending from the inner marginal edges of said corner pieces or risers beneath the bearing portions thereof in which the 100 bottom frame is journaled. The free end of each lug is turned outwardly at right angles to provide a stop piece 22, which when the end frame-members are swung upward to normal vertical position engages the 105 undersides of said longitudinal side portions 2 of said bottom member, thus limiting any further swinging movement of the end-member beyond the normal vertical plane, and since the opposite end member is interconnected 110 therewith by said top frame member, it too is stopped in normal vertical position.

In order to lock the rack or carrier in normal operative unfolded position, so that the same cannot collapse when in use, I provide 115 a locking means associated with the corner pieces or risers forming the opposite end frame-member. This locking means comprises an inwardly extending lug 23, connected with each of the laterally opposite 120 corner pieces or risers which form said opposite end member, the same extending from the inner marginal edges of said corner-pieces or risers, beneath the bearing portions thereof in which the bottom frame is journaled. I provide a laterally disposed slide-bar 24 having eye-ports 25 at its opposite ends embracing said side portions 2 of said bottom frame member, to dispose said slide-bar beneath the latter and longitudinally 125 130

slidable thereon. When the end frames have been raised to normal vertical position, said slide-bar 24 is pushed over the lock lugs 23, so that the slide-bar is disposed between the 5 latter and the bottom-member. The slide-bar 24 is thus positioned to obstruct any upward swinging movement of said lock lugs consequent upon the downward swinging of said end member to which the latter 10 are connected below the point of pivotal connection with said bottom-member, therefore locking the end members, as interconnected by the top-member in upwardly extending normal position.

15 The collapsible rack thus constructed provides a very useful utensil for the housewife, as well as for many other uses. When opened to normal position it serves as a rack or carrier for preserving jars, etc., the same 20 being inserted through the openings of the top-member and supported by the bottom member, so that a number of jars may be let down with the rack into the boiling water contained in the preserving kettle or 25 the like, or removed therefrom, without danger of scalding or otherwise injuring the hands. Other uses to which the rack may be put will readily recommend themselves without necessity of specifically mentioning 30 the same.

The rack is clean and sanitary, may be easily washed, and when not in use may be collapsed to occupy but little storage space.

I am aware that some changes may be 35 made in the arrangements and combinations of the several devices and parts without departing from the scope of my present invention as above described, and as defined in the following claims. Hence, I do not limit my 40 invention to the exact arrangements and combinations of the various devices and parts as hereinabove set forth, nor do I confine myself to the exact details of the construction of said parts as illustrated in the action 45 accompanying drawings.

I claim:-

1. A folding carrier comprising corner pieces, means interconnecting laterally opposite corner pieces, upwardly extending handle loops secured to and between laterally opposite corner pieces, a jar supporting bottom frame member pivotally connecting to said corner pieces, a jar embracing top frame member pivotally connected to said 50 corner pieces in vertically spaced relation to said bottom member, one pair of laterally opposite corner pieces having inwardly extending stop members adapted to engage the under side of said bottom member to 55 limit the unfolding movement of said carrier, the opposite pair of laterally opposite corner pieces having inwardly extending tongues, and a slide bar associated with said bottom member and said tongues to prevent 60 folding movement of said carrier.

2. In a folding carrier normally vertical corner pieces of flat stock, a jar supporting bottom member, a jar embracing top member spaced above said bottom member, the ends of said members having portions serving as journals, the inwardly presented marginal edges of said corner pieces being cut away to provide semi-circular bearing seats, and free tongues formed in the marginal edges of said corner pieces having reverse 70 semi-circular seat portions above said bearing seats, said tongues being adapted to be bent out of the respective planes of said corner pieces to provide gaps admitting said journal portions of said bottom and top 75 members into said bearing seats and then bent back into alinement with the latter to cause their reverse seat portions to straddle said journal portions to prevent displacement of said journal portions from said 80 seats.

3. A folding carrier comprising corner pieces, means interconnecting laterally opposite corner pieces, upwardly extending handle loops connected with the upper ends 90 of laterally opposite corner pieces, the inner marginal edges of said corner pieces being cut away to provide upper and lower semi-circular bearing seats, vertical tongues formed in the marginal edges of said corner 95 piece above said bearing seats, said tongues having reverse semi-circular bearing seats adapted to be alined respectively over said first mentioned bearing seats, a jar supporting bottom member pivoted by its ends in 100 said lower bearing seats of said corner pieces, a jar embracing top member pivotally associated in like manner with said upper bearing seats of said corner pieces, said tongues being adapted to be bent out of the respective planes of said corner pieces to provide 105 gaps admitting said bottom and top members to said bearing seats and then bent back into alinement with the latter to prevent displacement of said bottom and top members from the pivotal connections thus provided, stop means for determining the limit of the unfolding movement of said carrier thus formed, and lock means for maintaining 110 said carrier against collapsing when unfolded.

4. A folding carrier comprising corner pieces, means interconnecting laterally opposite corner pieces, upwardly extending handle loops connected with the upper ends 120 of laterally opposite corner pieces, the inner marginal edges of said corner pieces being cut away to provide upper and lower semi-circular bearing seats, vertical tongues formed in the marginal edges of said corner 125 pieces above said bearing seats, said tongues having reverse semi-circular bearing seats adapted to be alined respectively above said first mentioned bearing seats, a jar supporting bottom member pivoted by its ends in 130

- said lower bearing seats of said corner pieces, a jar embracing top member pivotally associated in like manner with said upper bearing seats of said corner pieces, said 5 tongues being adapted to be bent out of the respective planes of said corner pieces to provide gaps admitting said bottom and top members to said bearing seats and then bent back into alignment with the latter to prevent 10 vent displacement of said bottom and top members from the pivotal connections thus provided, one pair of laterally opposite corner pieces having inwardly extending stop-members beneath the pivotal connection of 15 said bottom-member therewith, said stop-members being adapted to engage the under side of said bottom member to limit the unfolding movement of said carrier, the opposite pair of laterally opposite corner pieces 20 having inwardly extending lock lugs beneath the pivotal connection of said bottom member therewith, and a slide bar associated with said bottom member adapted to be moved between said lock lugs and said bottom member to prevent collapse of said carrier.

5. In a folding carrier normally vertical corner pieces; a jar supporting bottom member comprising a rectangular frame consisting of side portions, end portions and intermediate longitudinally extending laterally spaced rods; a jar embracing top member comprising a rectangular open

frame consisting of side portions, end portions, and intermediate laterally extending longitudinally spaced members; means for pivotally connecting the end portions of said bottom member and said top member to said corner pieces in vertically spaced relation, one pair of laterally opposite corner pieces 35 having inwardly extending stop-members provided with outwardly turned stop lugs at their extremities, said stop-members being located beneath the pivotal connection of said bottom member with said corner 40 pieces so as to be carried into stopping relation with the side portions of said bottom member to limit the unfolding movement of said carrier, the opposite pair of laterally opposite corner pieces having inwardly extending lock lugs extending beneath the adjacent end of said bottom member, a transverse slide bar mounted on said side portions of said bottom member so that the same may be inserted between said bottom 45 member and said lock lugs to prevent the folding of said carrier, and vertical handle loops connected to and between the upper ends of laterally opposite corner pieces.

In testimony that I claim the invention 50 set forth above I have hereunto set my hand this 2nd day of March, 1918.
